DESCRIPTION

FIG. 1 is a front view of the first image in the sequence for a display screen with an animated avatar showing our new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof;

FIG. 9 is a front view of the ninth image thereof;

FIG. 10 is a front view of the tenth image thereof;

FIG. 11 is a front view of the eleventh image thereof;

FIG. 12 is a front view of the twelfth image thereof;

FIG. 13 a front view of is the thirteenth image thereof;

FIG. 14 is a front view of the fourteenth image thereof;

FIG. 15 is a front view of the fifteenth image thereof; and,
